UNITED STATES PATENT OFFICE

LOUIS J. LOEFFLER, OF STAPLETON, NEW YORK

DESIGN FOR A HAND TELEPHONE

Application filed June 5, 1930. Serial No. 35,908. Term of patent 14 years.

To all whom it may concern:

Be it known that I, LOUIS J. LOEFFLER, a citizen of the United States, residing at Stapleton, in the county of Richmond and State of New York, have invented a new, original, and ornamental Design for Hand Telephone, of which the following is a specification, reference being had to the accompanying drawing, forming part thereof, in which—

Fig. 1 represents a perspective view of a hand telephone embodying this design.

Fig. 2 is an end view of the same.

I claim:

The ornamental design for a hand telephone as shown.
